UNITED STATES PATENT OFFICE.

HOWARD M. DUDLEY, OF PHILADELPHIA, PENNSYLVANIA.

FABRIC-TREATING MACHINE.

1,306,529.

Specification of Letters Patent. Patented June 10, 1919.

Application filed June 5, 1918. Serial No. 238,297.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Fabric-Treating Machines, of which the following is a full, clear, and exact specification.

10 The device of my invention relates to fabric treating machines and refers particularly to machines suitable for steaming fabric rolls.

In the treatment of fabrics, it is sometimes essential that they be dyed, steamed or treated with air and one of the objects of my invention is a device in which any, or all, of these results may be accomplished.

My device is particularly suitable for the 20 steaming of wound fabric rolls and especially the treatment of the fabric by steam under pressure.

In the particular device of my invention, the fabric is wound upon a hollow foraminous reel and the fabric maintained thereon by means of a particular construction of mechanism whereby it will be retained in an undisturbed condition during the steaming operation.

30 The particular construction of the foraminous reel and its various parts as disclosed by my invention, allows of a uniform treatment of the fabric reel, thus producing uniform and even results.

35 My device is also adapted to the treatment of fabric rolls of varying widths and its use is therefore considerably extended.

In the particular form of the device of my invention as shown in the accompanying 40 drawings, similar parts are designated by similar numerals:

Figure 1 is a vertical cross-section of one form of my device.

Fig. 2 is a section taken upon the line 2—2 45 of Fig. 1.

Fig. 3 is a section taken upon the line 3—3 of Fig. 1, with the cover shown open in dotted lines.

Fig. 4 is a vertical cross-section of a modified form of my device.

Fig. 5 is a broken vertical cross-section

of a modified form of one of the blades of the foraminous reel.

Fig. 6 is a section through the line 13—13 of Fig. 7.

Fig. 7 is a broken side plan view of one of the blades of the foraminous reel.

Fig. 8 is a cross section showing a modified form of the members slidable upon the reel.

Fig. 9 is a section through the line 16—16 of Fig. 10.

Fig. 10 is a broken side plan view of a modified form of one of the blades of the foraminous reel.

Fig. 11 is a section through the line 18—18 of Fig. 12.

Fig. 12 is a broken side plan view of a modified form of one of the blades of the foraminous reel.

Fig. 13 is a section through the line 20—20 of Fig. 14.

Fig. 14 is a broken side plan view of a modified form of one of the blades of the foraminous reel.

The particular form of my device as illustrated comprises two hollow cylindrical members 20 and 21, between which is a series of spaced parallel plates 22, 22 supported upon the steps 23, 23, 24, 24 of the members 20 and 21. An imperforate cylindrical member 25, with a convergent end 26, is supported within the members 20 and 21 by the supporting members 27, 27. The cylindrical member 25 carries two annular ring members 28, 28 upon the arms 29, 29. The ring members 28, 28 have recesses within them into which the plates 22, 22 enter and are supported. Situated around and slidable over the members 20 and 21, and the plates 22, 22 are two angular annular members composed of the annular arms 30, 30 and 31, 31.

Pivotedly carried by each of the arms 30 is a series of threaded bolts, each carrying a threaded wing nut. An annular wedge-shaped member 35 is slidable over the member 20 and has a series of indents into which a bolt may be fitted. In order to make a tight joint between member 31, member 35 and the member 20, the packing 37 is inserted, the bolt placed within the indent and the wing nut screwed inwardly until a

tight joint is obtained. The inner surfaces of the members 30, 30 are serrated as at 38, 38.

- 5 A foraminous cover capable of placement around the fabric 100 comprises the two pairs of annular members 39, 39 hinged at 40 and capable of being maintained in a closed position by a clamp 41. The members 39, 39 have a series of cut-outs 42, 42, into 10 which may be fitted the angular members 43, 43, the inward extended arms 44, 44 of which have slots through which the arms 45, 45 of the serrated plates 46, 46 pass. The arms 45, 45 carry two stop-pins 47, 47 to 15 prevent the arms 45, 45 from leaving the slots in the arms 44, 44. By these means there is presented a series of parallel spaced serrated plates 46, 46 capable of placement upon the outer face of the fabric roll 100.
- 20 Upon the outer faces of each of the members 30 is a series of upwardly extended arms 50, 50 having an opening therein, through which there passes a bar 51 with the cross-head 52. The inwardly extended 25 end 53 of each of these bars is threaded to mesh with the right and left threaded turn-buckle 54.

The blades, or plates, 46, 46 are comprised of two members, offset at their inner ends 30 and slideable over each other, a spring 115 tending to distance the two members from each other.

In order to bind the blades 46, 46 upon the fabric roll, there are employed two annular members 110, 110, each formed of two parts pivoted at 111 and held in closed position by the clamp 112, the members 110, 110 being positioned in openings 113, 113 in the blades 46, 46.

- 40 The member 20 is extended into the hollow conical member 60 which, in turn, is extended into the hollow cylindrical member 61 revolvably supported within the bearings 62 of the standard 63. Fixedly attached to the member 61 is the cogged wheel 64 meshing with the worm-gear 65 revolvble within the bracket 66. The worm-gear is disconnected, or connected with the revolvble shaft 67 by means of the slide clutch 45 68, moved by the finger grip 69. The shaft 67 is fixedly attached to the pulley 70 which is revolved by a source of power not shown. The member 61 is connected by means of the bushing 71 with the non-revolvble pipe 55 72 which is connected with a source of liquid, air or steam.

The member 21 has an outwardly extended annular flange 73 abuttable upon the flange 74 of the conical member 75. There are a series of alined openings within the flanges 73 and 74, through each of which is placed a clamp 77 having a pointed member and the pointed threaded bolt 79 capable of insertion within indents of the flanges 73 and 74. By this means a tight joint may

be obtained between the flanges 73 and 74. Within the member 75 is the conical member 81, abuttable upon the member 25 and supported by the arms 82, 82. The member 75 is extended into the hollow cylindrical member 83, 83 revolvble within the bearing 84 of the standard 85. The member 83 is in abutment with the non-revolvble pipe 86 by means of the bushing 87, the pipe 86 being connected to a source of liquid, air 75 or steam.

The standard 85 has a centrally threaded opening 88 into which is threaded the bar 89 revolvble within the bearings 90 and 91. A handle 92 fixedly attached to the shaft 89 80 allows the ready revolution thereof and the consequent longitudinal movement of the standard 85. The bottom 93 of the standard 85 is dove-tailed into the plate 94 over which it is slidale.

In the modification shown in Fig. 4, the hollow members 75, 83 are replaced by the solid annular member 95, thus closing one end of the device.

In the modification of plates shown in 90 Fig. 5, the blade 22 is carried by the blade member 101 by means of a series of bolts 102, 102 slideable through openings in the members 101, 101, springs 103, 103 tending to distance the blades 22, 22 from the members 101, 101.

In the modification of the blades forming the foraminous cylinder, shown in Figs. 6 and 7, the blades instead of being serrated, carry a series of upwardly extended 100 triangular extensions 104, 104.

In the modifications of the blades forming the foraminous cylinder shown in Figs. 9 and 10, the blade 105 is diamond-shaped carrying the upwardly extended members 105 106, 106; in Figs. 11 and 12, it is diamond-shaped carrying the upwardly extended pointed member 107; and in Figs. 13 and 14 it is diamond-shaped carrying the serrated member 108.

In the modification of the slideable member 30 shown in Fig. 8, instead of the member 30 being of one piece and the member 39 of two pieces pivotally connected, the members 30 and 39 are integral, being 115 formed of the two members 120, 120' pivotally attached at 121 and capable of being clamped together at 122, 122'.

A drain pipe 123, carrying a valve 124, allows of the removal of condensed steam or 120 liquid from within the device.

The operation of the device is as follows:

The fabric 100 is wound upon the foraminous reel, the blades 46, 46 placed in 125 position within the members 39, 39 which are clamped together, the members 110, 110 are placed within the openings of the blades 46, 46 and brought together and clamped until the blades 46, 46 press firmly upon 130

the fabric rolls, the two members 30, 30 are brought to bear firmly upon the sides of the fabric roll by means of the turn-buckles 54, 54, a tight joint between the reel and the members 31, 31 accomplished by the members 37 and 35, 35. Steam is then passed through the pipes 86 and 72 into the interior of the reel, while the latter is revolved, the steam passing through the foraminous portion of the reel, the fabric roll and the foraminous cover.

The pipe system 83, 83, 75 shown in Fig. 1, may be readily dispensed with by substituting the closed end 95 shown in Fig. 4.

I do not limit myself to the particular size, shape, number or arrangement of parts as described and shown, all of which may be varied without going beyond the scope of my invention as described and claimed.

What I claim is:

1. In a fabric treating machine, in combination, a revoluble foraminous reel, means for revolving the reel, means whereby a portion of the openings of the foraminous reel may be closed whereby all of the steam introduced into the reel will pass through the fabric roll, a foraminous cover, means for pressing the cover upon the fabric roll maintaining it in position, and means for passing steam into the reel.

2. In a fabric treating machine, in combination, a revoluble foraminous reel comprising a series of spaced parallel blades, means for revolving the reel, means whereby

35 a portion of the openings of the foraminous reel may be closed whereby all of the steam introduced into the reel will pass through the fabric roll, a foraminous cover, means for pressing the cover upon the fabric roll maintaining it in position, and means for passing steam into the reel.

3. In a fabric treating machine, in combination, a revoluble foraminous reel comprising a series of spaced parallel blades, 45 means for revolving the reel, means whereby a portion of the openings of the foraminous reel may be closed whereby all of the steam introduced into the reel will pass through the fabric roll, a foraminous cover comprising a series of spaced parallel blades, means for pressing the cover upon the fabric roll maintaining it in position, and means for passing steam into the reel.

4. In a fabric treating machine, in combination, a revoluble foraminous reel, means for revolving the reel, means whereby a portion of the openings of the foraminous reel may be closed, a foraminous cover, means for pressing the cover upon the fabric roll maintaining it in position, imperforate means compressible against the ends of the fabric roll and means for forcing steam into the reel and through the fabric roll.

5. In a fabric treating machine, in combination, a revoluble foraminous reel com-

prising a series of spaced parallel plates, means for revolving the reel, means whereby a portion of the openings of the foraminous reel may be closed, a foraminous cover, means for pressing the cover upon the fabric roll maintaining it in position, imperforate means compressible against the ends of the fabric roll and means for forcing steam into the reel and through the fabric roll.

6. In a fabric treating machine, in combination, a revoluble foraminous reel comprising a series of spaced parallel blades, means for revolving the reel, means whereby a portion of the openings of the foraminous reel may be closed, a foraminous cover comprising a series of spaced parallel blades, means for pressing the cover upon the fabric roll maintaining it in position, imperforate means compressible against the ends of the fabric roll and means for forcing steam into the reel and through the fabric roll.

7. In a fabric treating machine, in combination, a revoluble foraminous reel, means for revolving the reel, means whereby a portion of the openings of the foraminous reel may be closed, a foraminous cover, means for pressing the cover upon the fabric roll maintaining it in position, imperforate means compressible against the ends of the fabric roll, an imperforate cylindrical member parallel to and within the reel spaced from the walls thereof and means for forcing steam into the reel and through the fabric roll.

8. In a fabric treating machine, in combination, a revoluble foraminous reel, means for revolving the reel, means slidable over the reel capable of abutting upon the edge of a fabric roll wound upon the reel, closing the openings of the reel exterior of the slid- 100 able members, a foraminous cover placeable around the fabric roll, means for forcing the cover upon the fabric roll maintaining it in position, means for forcing steam from within the reel through the fabric roll and 105 means for removing condensed steam.

9. In a fabric treating machine, in combination, a revoluble foraminous reel, means for revolving the reel, means slidable over the reel capable of abutting upon the edge of a fabric roll wound upon the reel, closing the openings of the reel exterior of the slid- 115 able members, a series of parallel spaced bars carried by the slidable members, means for longitudinally pressing the bars carried by 120 the slidable members, means for pressing the bars upon the fabric roll maintaining them in position, means for maintaining a tight joint between the reel and the slidable members and means for forcing steam through 125 the reel and the fabric rolls.

10. In a fabric treating machine, in combination, a revoluble foraminous reel, means for revolving the reel, means slidable over the reel capable of abutting upon the edge 130

of a fabric roll wound upon the reel, closing the openings of the reel exterior of the slideable members, a series of parallel spaced bars carried by the slideable members, means 5 for pressing the bars upon the fabric roll maintaining them in position, means for maintaining a tight joint between the reel and the slideable members, an imperforate

cylindrical member parallel to and within the reel spaced from the walls thereof and 10 means for forcing steam through the reel and the fabric roll.

Signed at New York, in the county of New York and State of New York, this 20th day of April, 1918.

HOWARD M. DUDLEY.
